UNITED STATES PATENT OFFICE.

FRANK KUHN, OF DETROIT, MICHIGAN.

ELECTRICAL HEATER.

1,130,987.

Specification of Letters Patent.

Patented Mar. 9, 1915.

Application filed January 5, 1914. Serial No. 810,469.

To all whom it may concern:

Be it known that I, FRANK KUHN, a citizen of the United States of America, residing at Detroit, in the county of Wayne and 5 State of Michigan, have invented certain new and useful Improvements in Electrical Heaters, of which the following is a specification, reference being had therein to the accompanying drawings.

10 The invention relates to electrical heaters of that type employed as toasters and for similar devices in which the heat is transmitted from the unit by radiation.

15 It is usual to provide a protecting casing for the heat radiating unit, and where the heater is used as a toaster it is also usual to provide hinged supports for holding the bread or other material in position for toasting.

20 The present invention has particular reference to the construction of this protecting frame, and it is an object to form said frame from sheet metal stampings.

25 In the drawings: Figure 1 is a perspective view of the heater as designed for a toaster; Fig. 2 is a cross section; Fig. 3 is a longitudinal section through a portion of the instrument; and Fig. 4 is a horizontal section.

30 The heating unit A is preferably in the form of a flat armored resistor, having terminal contacts B projecting laterally from the lower portion thereof.

35 C is the frame which is formed from sheet metal stampings and is of the following detailed construction: D is a base member struck up from sheet metal to form depending edge flanges D' and having a central longitudinally-extending slot E for the passage of the heating element, this being provided with the laterally-extending slots E' for the passage of the terminals B. F and F' are vertical frames, which are struck out from sheet metal and are provided with inwardly-extending marginal flanges G at the top and the sides thereof. These members F and F' are cut away opposite the resistor to avoid obstructing the radiation, but crossing this cut-away area are bars H, which are 45

50 twisted so as to expose only the edges thereof to the radiating surface of the unit. At the opposite edges of the frame the flanges G are provided with inward extensions I, which are bent to form grooved guides for 55 engagement with the edges of the heating

element A, and holding the same in central position between the two members F and F'. Inwardly-projecting lugs J upon the members F and F' also form guides for the heating element, and the latter is supported, after being inserted through the slot E in the base, by pins or bolts K passing transversely across the lower portion of the members F and F'. The frame is also preferably provided with a flat grating top L, 60 which is struck up from sheet metal, and has the downturned edge flanges L' and the downturned tapering end portions L''. The latter extend inward to underlap a portion of the top flanges G of the members F and F', to which they are secured, preferably by spot-welding, as indicated at M. The lower portions of the frames F and F' are preferably slightly flared or spread outward and are secured to the base D by tongues N passing through slots in said base and bent under the same. The hinged frames, or toast supports O are also preferably formed from sheet metal and are cut away to form an open grating. The lower ends of these 70 members engage a rod P which forms the hinge connection with the body of the frame, engaging outwardly-projecting lugs Q thereon, while a spring R upon the rod causes a resilient clamping connection. The upper 75 edge of the member O is turned over a wire S which forms a beaded edge, while projecting portions S' of the wire form handles for turning down the frames.

80 The construction as described is one that is inexpensive to manufacture, being formed almost entirely of sheet metal stampings, which are easily assembled without the use of bolts other than those which support the heating element. The construction also has a 85 pleasing appearance, as the flat faces of the sheet metal which are exposed to view give the effect of a solid and substantial construction. On the other hand, by the use of sheet metal in place of castings, the weight is 90 greatly reduced, while the strength is even greater. If desired, the base D may be supported upon non-metallic foot pieces T arranged at the corners as shown.

95 What I claim as my invention is:— 105

1. A frame for electric heater, comprising a pair of complementary sheet metal stampings having inturned edge flanges abutting against each other, and a portion of said stampings being cut away to form open 110

- areas crossed by transversely-extending integral bars, said bars being twisted to expose the edges only in the open areas.
2. A frame for electric heater, comprising a pair of sheet metal stampings having transversely-extending marginal flanges abutting against each other, the opposite edges being provided with inturned flanges, forming a guide and support for the heater element, and the portion intermediate the edges being cut away to form open areas crossed by integral bars.
3. A frame for electric heater, comprising a pair of sheet metal stampings having edge flanges bent transversely and abutting against each other to space the parallel portions of said stampings, said parallel portions being cut away to form open areas crossed by integral bars which are twisted to expose the edges only in said open areas, a base upon which said stampings are mounted secured to the lower ends thereof, and a top secured to the upper ends of said stampings.
4. A frame for electric heater, comprising a pair of sheet metal stampings cut away to form open grids, the edges of said stampings being turned in to abut against each other, a top formed of a sheet metal stamping having downturned ends secured to the top flanges of said pair of stampings, and a sheet metal base to which the lower ends of said pairs of stampings are secured, said base being slotted for the insertion of the heating element therethrough and in between said pair of stampings.
5. A frame for electric heater, comprising a sheet metal base having downturned marginal flanges, a sheet metal top having edge flanges and downturned ends, and a pair of sheet metal stampings extending vertically intermediate the base and the top, having side and top flanges bent inward and abutting, and secured to the downturned ends of the top, the lower ends of said pair of stampings having a bent tongue engaging with said base.
6. A frame for electric heater, comprising a sheet metal base having downturned marginal flanges, a sheet metal top having flanged edge portions and downturned ends, and a pair of complementary stampings extending vertically between said base and top, said stampings being cut away to form open areas crossed by integral bars, and the edge portions of said stampings being turned in and abutting to form closed ends.
7. A frame for electric heater, comprising a sheet metal base, a sheet metal top, complementary sheet metal stampings extending vertically between said base and top, and each formed with open areas with transversely-extending integral bars and flanged edges abutting against each other, the side edges having inward extensions forming grooved guides for engaging the heating unit, and hinged supports secured to said complementary stampings, being also formed of sheet metal stampings.
8. A frame for electric heating unit, comprising a pair of complementary sheet metal stampings having flanged edges abutting, with inward extensions at the opposite sides forming grooved guides for receiving the heating unit, a slotted base secured to said complementary stampings and through which the heating unit is inserted into engagement with said grooved guides, and detachable transversely-extending pins for supporting said unit when engaged with said guides.
9. A frame for electric toaster, comprising a pair of complementary sheet metal grid stampings, having marginal abutting flanges for spacing the grids, the cross bars of said grids being twisted to present the edge only in the open area, and a hinged support formed of a sheet metal stamping having untwisted bars opposite the twisted bars of said grids.
10. A frame for electric toasters, comprising a sheet metal grid stamping having twisted cross bars exposing the edges only in the open area, a hinged frame formed of sheet metal having untwisted bars opposite said twisted bars, a rod connecting the ends of said bars and forming a hinge, and a rod forming a beaded edge for the upper end of said hinged frame and extending outward to form an operating handle.
11. A frame for an electric heater, comprising a pair of complementary sheet metal members having flanged edges, a portion of said members being cut away to form open spaces with intermediate transversely-extending bars, said bars being twisted to expose the edges only in the open area.

In testimony whereof I affix my signature in presence of two witnesses.

FRANK KUHN.
